I, Andrew McIlroy, and Hugh T. McIlroy, both of Saginaw, Michigan, have devised a novel ironing board having a rigid triangular framework and a self-supporting structure.

UNITED STATES PATENT OFFICE

01. **1,987,218**

FOLDING IRONING TABLE

Charles W. Sadenwater, Saginaw, Mich., assignor to Saginaw Manufacturing Co., Saginaw, Mich., a corporation of Michigan

Application January 29, 1934, Serial No. 708,793

2 Claims. (Cl. 68—10)

52. **This invention relates to folding ironing tables having collapsible legs that can be folded flat against the ironing board for storing.**

The invention pertains more particularly to such tables wherein the board has a centrally arranged front leg and a pair of rear legs pivoted to its under side, with connecting rods pivoted to the front leg near its foot and to the rear legs intermediate their ends. There is also a jointed

10. or toggle locking rod member which holds all the other members rigidly in position when the table is extended for use.

This application is in part a continuation of my co-pending application, Serial No. 691,602, 15. wherein is described and claimed a structure of the above character, including a latching device by which the locking rod member or brace is releasably fastened to the front leg when the table is set up for use so as to prevent the legs from 20 becoming folded accidentally, and enabling the user to unlatch the parts easily before folding them.

The present application provides a somewhat similar system of bracing for the legs, yet arranges the locking bar and its latching device in a new way, whereby the objects of the invention are attained.

These objects are to simplify the construction, provide a supporting mechanism having stability, 30 reducing the cost and facilitating the manufacture of the table.

My improvement, therefore, is found in the supporting structure arranged so that changing the board on a given set of legs can be accomplished easily and quickly and the shop assembly 35 of these parts is facilitated, reducing the cost of manufacture.

My improvement also includes a novel means 40 whereby the toggle-like locking member is enabled to latch itself in a straightened position and to make it easy for the user to unlatch it and fold all the supporting parts by a single breaking-down movement of the toggle.

With these objects in view I have devised and 45 invented the improved ironing table that is illustrated in the accompanying drawing and described herein, my claimed invention residing in the particular construction and arrangement of the toggle-like locking rod members and the 50 manner in which they are hinged and connected together between the rear legs and the top of the front leg so as to provide a rigid framework that is capable of standing rigidly.

In the accompanying drawing Fig. 1 is a side 55 view of the table with the legs extended in work-

ing position, the board being in place and the direction of movement of the toggle joint while the legs are being folded being indicated by a broken line.

Fig. 2 is a fragmentary enlarged detail of the parts constituting the locking rod member and the latching device. The same reference characters indicate the same parts in the several views.

To the ironing board 1 are hinged a centrally arranged front leg 2 and a pair of spaced rear legs 3. Connecting rods 4 are pivoted at 5 to the front leg 2 near its foot and to the rear legs intermediate their ends at 6. The toggle or locking rod member consists of two bars 7 pivotally connected to the rear legs at 6. The bars 7 converge forwardly and each is pivoted at 8 to one of the side bars 9 of a toggle member 10. The other ends of side bars 9 are pivoted to the hinges of leg 2, as shown at 11. The bars 9 are spaced 20 apart a distance equal to the thickness of the front leg 2 so that when the parts are folded they will lie close alongside the legs 2. The member 9 swings forward and upward as indicated by the broken line in Fig. 1 to fold the table, and compactness for shipment and neat appearance when folded are thus attained. The longitudinal upper edges of bars 9 are parallel and are preferably connected by a suitable web member or spacer, as shown in Fig. 2.

Near the pivot 8 is an abutment 12 which is struck up from bar 9 near its upper edge, and near its lower edge is a projection 13. The free end 14 of bar 7 is adapted to ride over the projection 13 when pivot 8 of the member 10 is 35 pushed downward in the manner indicated by the broken line in Fig. 1. The part 14 is releasably locked between 12 and 13 in the manner shown in Fig. 2 by a reverse or upward swinging movement of the joint 8, so as to hold the members 7 and 10 in the straightened position shown in Fig. 1 and joint 8 is prevented from going higher. Folding or extending is thus accomplished by a single movement, and the table is 40 designated in the trade as a "one movement ironing table". In the position shown, the parts 7 and 10, together with leg 2 and connecting rods 4, constitute a rigid triangular non-racking truss frame structure that has its apex at 11 and rests on the floor at its lower corner 5, tending to keep 45 the legs 3 upright. The self-supporting framework will hold that position while a board 1 is being removed and another board is being put in its place and fastened to plates 15 and 16 carrying the pivots for plates 3 and 2 respectively. 50 55

Legs 3 are prevented from pivoting about 6 as a center and the triangular frame 2, 4 and 7, 9 is prevented from collapsing and dropping to the floor by reason of the triangular shape of the frames defined by the parts 3, 4 and the floor, and by the parts 4, 2, 10, 7. A triangular pivoted framework can not be "racked", so, barring sliding of the bottoms of legs 3 and 2 on the floor, the framework must retain its position without the board 1. Similarly, the frame 4, 2, 7 is rigid and non-racking because of its triangular structure, and will not collapse. This general arrangement of the legs, together with the novel toggle-like foldable locking device exemplified by the structure illustrated in Fig. 2 constitutes a new and useful improvement in foldable ironing tables whereby a single breaking-down movement of the toggle suffices to fold all the supporting parts, as has been pointed out in the statement of the invention.

For rapid assembly in the factory the board 1 can be laid down flat on a floor or table and the framework, extended as shown in Fig. 1, can be turned upside down without collapsing and can be secured to the board.

The distance between plates 15 and 16 is of course a standard distance for any given leg assembly and is kept the same for all the different boards 1 which may be applied to the legs. This can be done conveniently by using a standard measuring stick or gauge.

It is thus seen that the present improvement provides a simple, effective, inexpensive structure that enables the leg assembly to be applied easily and quickly to different shapes or sizes of boards, as desired.

Having thus described my invention, what I claim and desire to secure by Letters Patent is:

1. In an ironing table having a board, rear legs and a central front leg hinged thereto, in combination, a toggle-like locking brace consisting of a pair of bars converging toward their front ends and pivoted at their rear ends to said rear legs, and a member comprising a pair of side bars spaced apart by the thickness of the front leg, said bars being substantially parallel and hinged at their front ends to the hinge connection of the front leg to the board and hinged at their rear ends to the convergent ends of said bars, and stop members associated with said convergent ends and arranged to prevent an upward movement of the said toggle-like brace from its straight position, means to releasably hold the same against downward movement and means for holding the front leg in its board-supporting position.

2. In an ironing table having a board, rear legs, and a central front leg hinged thereto, in combination, a toggle-like locking brace consisting of a pair of bars converging toward their front ends and pivoted at their rear ends to said rear legs, and a member comprising a pair of substantially parallel side bars spaced apart by the thickness of the front leg, said bars being hinged at their front ends to the hinge connection of the front leg to the board and hinged at their rear ends to the convergent ends of said bars, and means for releasably locking said toggle-like brace in its straight position.

CHARLES W. SADENWATER.
